UNITED STATES PATENT OFFICE.

HARRY S. FRANK, OF ST. LOUIS, MISSOURI.

PISTON-RING.

1,400,672.

Specification of Letters Patent. Patented Dec. 20, 1921.

Application filed December 7, 1918. Serial No. 265,721.

To all whom it may concern:

Be it known that I, HARRY S. FRANK, a citizen of the United States, residing at the city of St. Louis and State of Missouri, have 5 invented a new and useful Piston-Ring, of which the following is a specification.

This invention relates to piston rings.

An object of the invention is to provide a novel and efficient piston ring composed 10 of a single piece of metal in the form of two open bands, one of which is within the other, and which ring is capable of free expansion and contraction in order to function properly as a piston ring.

15 Another object of the invention is to provide an improved piston ring of the open resilient type composed of a plurality of coils one within the other and having integral connection whereby relative displacement of the coils is prevented.

20 Other objects of the invention will appear from the following description in which reference is made to the accompanying drawings illustrating different forms of 25 the invention, and in which—

Figure 1 is an elevation of a blank from which a ring may be made.

Fig. 2 is an elevation of the blank after it has been cut to form a spiral element 30 preparatory to the formation of the ring.

Fig. 3 is an elevation of a finished ring made from the spiral element illustrated in Fig. 2.

35 Figs. 4, 5 and 6 are elevations of modified forms of rings.

Fig. 7 is a side elevation of the ring shown in Fig. 3.

Fig. 8 is a side elevation of another form of ring which, viewed from another elevation, is the same as that illustrated in 40 Fig. 3.

Fig. 9 is a side elevation of the types of rings illustrated in Figs. 5 and 6.

45 Figs. 10, 11 and 12 are views illustrating different joints for the ends of the rings.

Fig. 13 is a cross sectional view on the line 13—13 of Fig. 7.

Fig. 14 is a cross sectional view on the line 14—14 of Fig. 8.

50 Fig. 15 is a cross sectional view on the line 15—15 of Fig. 6.

Fig. 16 is a cross sectional view on the line 16—16 of Fig. 5.

55 Fig. 17 is a cross sectional view on the line 17—17 of Fig. 4.

In order to comprehend clearly the char-

acteristics of my improved piston ring it is appropriate to refer briefly to the manner in which the ring may be made. The manner in which the ring may be made may 60 be understood more clearly by making reference to Figs. 1 and 2 of the drawings. In Fig. 1 a form of blank is shown for the manufacture of the ring shown in Figs. 3 and 7. It is unnecessary to illustrate the 65 blanks for the construction of the other forms of rings shown in the drawing, since the manner in which they may be made from the blanks will be clearly understood from the description of the manner in which 70 any one form of the rings may be made.

As shown in Fig. 1 the blank is an integral element and in the manufacture of the ring the first step after the blank is obtained is the step of cutting or sawing the 75 blank to provide a spiral element, one form of which is shown in Fig. 2. The cut or slot 1 which is formed is continuous so that the length of the spiral element resulting from the formation of the slot is almost 80 double the circumference of the blank. The spiral element which is formed by cutting is capable of being pressed or flexed to place one of the bands or rings thereof within the other. As will readily be understood by 85 reference to the drawing the spiral element is provided with a shoulder 2 thus really providing two spiral bands which are integrally united; one of which bands is adapted to be placed within and encircled by the 90 other.

As shown in Fig. 1, the adjacent edges of the spirals are integral; and as shown in Fig. 2, the spiral element is formed by cutting sufficient material from the edge there- 95 of and from between the spirals to produce a spiral member or element which is of uniform width throughout its length. This may be done by taking from the outer edges of the blank, material equal to the width 100 of the slot.

After the spiral element has been formed as described above, or in any other manner, the two integrally united bands or rings are placed one within the other and while in that position or adjustment they are subjected to treatment in order to set the material in the changed shape, so that when the pressure is removed the product that remains will consist of a ring composed of an outer 110 band and an inner band which are integrally united at one point and which have

their opposite ends free in order to permit proper functioning of the device as a piston ring. As will be understood by reference to Figs. 7, 8 and 9, one end only of the inner band is integrally united with the opposite end of the outer band; thus leaving the opposite ends of the bands free for expansion and contraction of the ring which is composed of two bands, one encircling the other.

10 The treatment to which the ring is subjected when one of the bands thereof is placed within the other may include heating the ring to the proper and necessary temperature to change the molecular arrangement; or, the treatment may consist of hammering the ring to attain that result; or, the ring may be otherwise subjected to treatment to set the material thereof in the shape desired.

15 20 In whatever manner the material is treated the surfaces of the ring are ground off or finished either before or after the treatment is complete.

25 As shown in Figs. 3 and 7 the ring comprises an outer band or ring 3 and an inner band or ring 4 integrally united with each other at their opposite ends by overlapping connection 2. In the form of the ring shown in Figs. 3 and 7 the inner and outer bands 30 are of equal width and approximately equal radial thickness throughout the circumference of the ring; though this construction may be varied as will be understood by reference to some other forms of the invention 35 illustrated.

40 The ring shown in Figs. 4 and 17 consists of an outer band 5 and an inner band 6 integrally united at 2 as in the case of the ring shown in Fig. 3. The outer band 5 is formed with an inwardly extending flange 7, the inner periphery of which lies in the same plane with the inner periphery of the band 6; and the inner band 6 is provided with a circumferential flange 8 the outer edge of 45 which is in the same annular plane with the surface of the band 5.

50 The form of ring illustrated in Figs. 5 and 16 is composed of an outer band 9 and an inner band 10 integrally united at 2, and having a circumferential groove 11 in which the outer band is seated. The groove 11 is of sufficient depth to receive the outer band so that the periphery of the outer band is in the same plane with the periphery of the inner band at each side of the groove.

55 60 The ring illustrated in Figs. 6 and 15 is composed of an outer band 12 and an inner band 13 integrally united at 2 as in the case of the other rings described. The outer band 12 is of less width than the inner band, the latter being formed with a circumferential flange 14 at one side of the band 12, having its edge in the same annular plane with the periphery of the band 12.

65 70 75 80 85 90 95 100 105 110 115 120 125 130 The form of ring illustrated in Figs. 8

and 14 is composed of an outer band 15 and an inner band 16 integrally united at 2. The bands 15 and 16 have matching inclined surfaces which contact with each other as shown in Fig. 14, so that there is a slight 70 tendency for the inner band to press the outer band laterally toward one side, thus closing the groove in the piston in which the ring may be mounted.

Various other forms of the invention may suggest themselves from the forms disclosed and I do not confine myself to the specific formation shown in the drawing. It will be apparent also that various forms of joints may be provided for closing the space between the end of the outer band and the adjacent shoulder 2 uniting the inner and outer bands. For instance, as shown in Fig. 10, the end of the outer band may be formed with a projection 17 adapted to operate into a notch or recess at the side of the shoulder 2 and overlap a matching projection 18 on the shoulder 2. Thus, the space between the end of the outer ring and the shoulder will be closed when the ring is compressed. If desired, the end of the outer ring may be formed at an angle as shown in Fig. 11, in which the outer ring has an angular terminal 19 adapted to co-operate with a similarly shaped wall on the shoulder 2. The form of the joint illustrated in Fig. 12 includes a notch 20 in the end of the outer band and a projection 21 on the shoulder 2 adapted to be received within the notch 20 and thus close the space and prevent the passage of gas 100 when the ring is compressed within the cylinder.

It is obvious that various other forms of joints may be provided in order to prevent the passage of gas or steam between the end 105 of the outer band or ring and the adjacent shoulder.

It is well known that a piston ring must be of a diameter larger than the internal diameter of the cylinder in which it is to be used. In the manufacture of piston rings heretofore in some cases the rings have been made from blanks of a diameter which is too small for the cylinders in which it is desired to use the rings. In such cases the rings are expanded to the desired dimensions and set in their expanded shape so that they will impart the necessary pressure against the cylinder walls in the operation of the piston. In other cases rings have been made from blanks of the desired size so that it is unnecessary to expand the rings. It is obvious that rings may be manufactured in either way, and still embody the principles of my invention.

What I claim and desire to secure by Letters Patent of the United States, is:—

1. A piston ring, comprising a single piece of homogeneous metal composed of a number of coils distorted axially one within the 130

other, and an integral connection uniting said coils and having a radial thickness equal to the combined thickness of said coils.

2. A piston ring, composed of a single piece of homogeneous metal and comprising an inner annular band, an outer annular band of the same width as the inner band encircling the inner band, and an homogeneous connection having a radial thickness equal to the combined thickness of said two bands uniting one end of the inner band with the opposite end of the outer band and having its outer surface on the same radius of curvature as the outer surface of the outer band.
3. A piston ring comprising a spiral, having an inner convolution and an outer convolution united by an integral connection, the cross section of said connection conforming to the combined cross-sections of said convolutions, said convolutions having a

tendency to expand radially, each of said convolutions being of trapeziform cross-section and including a side in contact throughout its length with the corresponding side of the other convolution. 25

4. A piston ring comprising a spiral, having an inner convolution and an outer convolution united by an integral connection, the juxtaposed faces of said convolutions being beveled and in contact with each other throughout their lengths. 30

5. A piston ring comprising a spiral, having an inner convolution and an outer convolution united by an integral connection, 35 the cross-section of said connection conforming to the combined cross sections of said convolutions, said convolutions having each a bevel face, said beveled faces contacting throughout their lengths.

HARRY S. FRANK.
